UNITED STATES PATENT OFFICE

2,487,210

BRASSIÈRE

Rae Barco, Bronx, N. Y.

Application May 21, 1946, Serial No. 671,158

1 Claim. (Cl. 2—42)

1

This invention relates to brassières.

Broadly, it is an object of my invention to provide a brassière with stiffened members at the middle part of the brassière positioned to separate the breasts and to provide stretchable and non-stretchable means to support the breasts.

More particularly, it is an object of my invention to provide non-stretchable and stretchable supports directed upwardly and outwardly to support the breasts, keep the brassière in place and maintain its shape.

Another object is to support the breasts in such a manner as to give smaller breasts a larger appearance and larger breasts a smaller appearance and to hold the breasts in a more natural position and without constriction.

Still another object is to provide a brassière particularly adapted for women with heavy busts to properly support and retain the brassière in position upon the wearer.

For a fuller understanding of the nature and objects of my invention, reference is had to the following detailed description in connection with the accompanying drawing, in which is shown one of the embodiments of this invention.

Fig. 1 is a plan view, partly in perspective, showing the inside of the brassière.

Fig. 2 is a front view of the brassière shown in position upon the figure.

Fig. 3 is a section taken through line 3—3 of Fig. 1.

Referring to the drawing, numeral 10 designates a brassière comprising a pair of breast pockets 11, a central reinforcing piece 12 stitched between pockets 11 along the vertical upper central portion of the brassière. Stitched to the lower edges of the pockets 11 is a lower section 13 having reinforcing strips 14 and 15 joined together by open work stitching 16. At the central portion of pockets 11 and running upwardly and outwardly are open seams or pleats 17 which run to the center of pockets 11. On either side of the pockets 11 there are stitched back pieces 18 joined by reinforcing tapes 19 to the sides of pockets 11. At the extremities of back pieces 18 strap members 20 and 21 are provided; straps 20 having a series of eyelets while strap 21 has a hook 23 for fastening into any of the eyelets 22 for adjustability. At the upper portion of pockets 11 the brassière is provided with shoulder straps 24 which are connected to the back pieces 18, the straps being adjustable as is well-known in the brassière art. A reinforcing tape 25 is stitched around the edges of the back pieces 18, breast pockets 11 and lower section 13.

2

I have provided improved means for reinforcing the brassière at the front central portion between the breast pockets 11 for separating and supporting the breasts and to keep the brassière in proper position and to aid in uplifting the breasts. To accomplish this I have stitched to the inside of the brassière at the central portion thereof a pair of upwardly converging pockets 26 in which there are sealed stiffening members 27 throughout the length of pockets 26, both pockets forming an inverted V. Attached to the outer edges of pockets 26 are a pair of opposed converging non-stretchable members 28, the ends of which are stitched to an elastic member 29 which begins at the central portion of pockets 26 and extends at right angles to pockets 26 and are directed upwardly crossing approximately the central portion of pockets 11. The end of one of said members contains a series of eyelets 30 while the end of the opposite member 29 contains a hook 31 adapted to be used with eyelets 30 for adjusting the length of elastic members 29. The elastic member 29, which stretches between the edges of pockets 26 and the point where the non-elastic members 28 join the elastic member 29, provides a resilient central cradle for maintaining the inside portions of the breasts in separated and non-restricted position.

At the front central portion I have inserted a reinforcing member 32 which follows the line of the strips 14 and 15. The reinforcing member 32 acts as a terminal for the bottom of pockets 26 and also acts to strengthen the front central portion of the brassière and further aids in the support of the lower portion of the breasts.

It will be noticed in Fig. 2 that the triangular support, created by converging pieces 28 and the central elastic piece, separates and supports the breasts giving larger breasts a smaller appearance. By supporting and lifting smaller breasts, such breasts will be given a larger appearance.

It is obvious that various changes and modifications may be made in my preferred embodiment herein described. However, it is to be understood that various changes and modifications may be made in the details of construction without departing from the general spirit of the invention.

50 I claim:

A brassière of the character described having a body girdling portion having pleats extending upwardly of said body girdling portion at spaced distances from the middle of the front thereof and terminating at a distance from the upper

edge thereof so as to provide a fullness coming to a peak at the upper end of said pleat, a pair of straight stiffened members at the front central part of said brassière which converge upward at an angle to one another in the form of an inverted V, the upper center of said inverted V attached to the top central edge of said brassière, said stiffened members positioned one between each of said pleats and the middle front of said brassière, a stretchable member attached at the center of each stiffened member for lateral tension, said stretchable members extending outwardly from said stiffened members and underlying the upper part of said brassière, a pair of non-stretchable straps of equal length attached at the opposed ends of each of said stiffened members, the other ends of said non-stretchable straps attached at a single point

along said stretchable member at said peak forming opposed triangles and providing resilient support and spacing means for the breasts of the wearer.

RAE BARCO.
